(57) **CLAIM**

The ornamental design for a foot massager, as shown and described.

DESCRIPTION

FIG. 1 is a top plan view of a foot massager showing our new design;

FIG. 2 is a bottom plan view thereof;

FIG. 3 is a left side view thereof;

FIG. 4 is a right side view thereof;

FIG. 5 is a top perspective view thereof; and,

FIG. 6 is a bottom perspective view thereof.

The broken lines shown in the drawings are for the purpose of illustrating portions of the foot massager, which form no part of the claimed design.
